H. MATTHEWS

PICTURE

Filed July 30, 1926

FIG. 1.

FIG. 2.

Inventor:
Homer Matthews
by F. Weston Lamp & Co
Attest

UNITED STATES PATENT OFFICE.

HORATIO MATTHEWS, OF EALING, LONDON, ENGLAND.

PICTURE.

Application filed July 30, 1926, Serial No. 126,067, and in Great Britain December 10, 1925.

The present invention has for its object to provide an improved method of treating pictures which are to be viewed by transmitted light and particularly where such pictures are to be employed in combination with a device such as a rotary multi-coloured screen revolving around the source of light for changing the lighting effect by which the picture is illuminated.

Whereas pictures intended to be viewed by transmitted light are usually treated on the back with pigments in the usual method of the artist, according to the present invention stencilled coloured papers or masks are employed, patterns being cut out of the coloured papers in such manner as to produce the desired effect when the said papers or masks are placed against the back of the picture.

The stencilled coloured papers may be used alone or in combination with painted portions of the picture. A light-diffusing screen, plain or coloured, is employed between the back of the picture and the source of light.

When such pictures are illuminated through the medium of a multi-coloured rotary screen producing the changing coloured effects, such as sunset or sunrise, the coloured paper stencils or masks particularly when applied to the background or sky portion of the picture enhance or intensify by comparison the changing light effects on the other portions of the picture.

In the accompanying drawings,—

Fig. 1 is a back view of a picture prepared in accordance with the present invention for being viewed by transmitted light.

Fig. 2 is a sectional elevation showing a picture such as illustrated in Figure 1, combined with an illuminating apparatus of the kind having a multi-coloured screen rotated about a lamp by a propeller device or vanes operated by the heat of the lamp.

In Fig. 1 the outline of the picture *a* on the front which in this instance consists of a photograph of a motor car, is shown in dotted lines.

b is a stencil of thin blue paper cut to a pattern so as to cover only the sky portion of the picture *a* and following the outline of the upper and end portions of the car.

Some portions of the car and the road may be coloured on the back of the picture by means of pigments in the usual manner.

c is a frame in which the picture *a* is

mounted, and *d* is a light-diffusing screen mounted on a frame *e* which is secured to the back of the picture *a* or its frame *c* so as to be spaced a short distance therefrom to diffuse and soften the lighting effect.

In Figure 2 the frame *c* with the picture *a*, stencil *b*, frame *e*, and light-diffusing screen *d* is adapted to slide into and out of the front of a casing *f* so as to enable the pictures to be changed as required.

The casing *f* is provided with a hinged top *g* and in the bottom of the casing is fitted an electric lamp *h*, the socket of which is arranged in the base of a semi-cylindrical hood or reflector *i*, on the top of which is rotatably mounted a bell shaped multi-coloured transparent screen *j*, the bearing of which consists of an inverted cup *k* secured centrally of the screen *j* and mounted on a pin *k'* on the top of the hood *i*.

The top of the screen *j* is formed with propeller vanes *l* so that the screen *j* is slowly rotated by the hot air arising from the lamp.

The screen *j* is divided vertically into two semicircular portions or segments *m* and *n*, the one of a reddish colour and the other of a bluish colour.

This screen *j* is made of very thin material and the adjacent edges of the segments *m* and *n* are so arranged as to abut and thus avoid any shadow when the said adjacent edges are passing between the lamp and the picture.

In use, when the lamp is switched on and the multi-coloured screen *j* slowly rotated, the reddish and bluish segments thereof pass alternately between the lamp and the picture producing a changing sunset or sunrise effect or sunshine or cloud effect on the picture when viewed from the front, and by the use of the stencilled paper or mask *b* covering the sky or upper background this changing sunlight effect is concentrated on the motor car and enhances the alluring and attractive appearance of the picture.

What I claim as my invention and desire to secure by Letters Patent is:—

1. The combination with a picture intended to be viewed by transmitted light, of a coloured translucent stencil sheet applied to the back of the picture over those parts that are not to be intensively illuminated, a light diffusing screen located a short distance from the back of the picture, a source

of light and a multicoloured rotating screen surrounding the source of light.

2. The combination with a picture intended to be viewed by transmitted light, of a coloured translucent stencil sheet applied to the back of the picture, its body portion covering the parts of the picture that are not to be intensively illuminated, and the margin

of its cut-away portion registering with the outline of the parts of the picture that are to be intensively illuminated, a light diffusing screen located a short distance from the back of the picture, a source of light and a multicoloured rotating screen surrounding the source of light.

HORATIO MATTHEWS.
